CONTROLLABLE RADIOACTIVE VOLTAGE CHARGING DEVICES

Paul Rappaport, Princeton, N. J., assignor, by mesne assignments, to the United States of America as represented by the Secretary of the Air Force

Application October 1, 1952, Serial No. 312,477

8 Claims. (Cl. 310—3)

This invention relates generally to voltage chargers and more particularly to an improved voltage charging device utilizing a radioactive isotope and having a controllable output voltage.

In the prior art, voltage charging or voltage generating devices have been devised in which a radioactive source of charged particles is positioned in a vacuum and produces high energy charged particles which subsequently are collected to establish an electric potential. The use of a vacuum was necessary to prevent gas ionization between the radiation source and a collector electrode for collecting the charged particle radiations. Such ionization would cause a substantial if not complete reduction of the electrical charge desired. However, in a copending application Serial No. 177,015 filed August 1, 1950, by Ernest G. Linder radioactive voltage charging apparatus is described and claimed wherein comparatively low potentials may be established in a normal atmosphere. In said application a dielectric material is interposed between the radiation source and the collector, the dielectric material preventing the flow of low energy ionized particles therebetween which would tend to reduce the potential to which the device charges.

While the Linder apparatus is effective in affording voltage charging in air or other atmospheres, the device inherently charges to some relatively high final voltage which is a function, for example, of the quantity and type of radioactive isotope used, the conductivity and thickness of the dielectric material, and other factors. The voltage thus derived is high (of the order of several thousand volts). However, most fields of application for such devices require substantially lower voltages. These lower and desired voltages, rather than the voltage to which the device naturally charges, may be achieved in one instance by utilizing voltage dividers. To achieve such voltages, however, relatively expensive dividers comprising resistors having resistances of the order 10^{12} to 10^{14} ohms may be required. Since such resistors are not readily attainable at many different specified values, it is extremely difficult to obtain a particular desired output voltage. Also, such resistors are bulky and considerably increase the overall size of the charging apparatus.

According to the instant invention, an improved low voltage radioactive charging device is disclosed and claimed in which the output voltage of the device may be limited as desired by providing a controlled ion leakage path intermediate the radiation source and the collector electrode. This ion leakage path effectively shunts the charger and comprises an aperture located in the dielectric material and in the path of the high energy charged particles emitted by the radiation source. The equivalent resistance of the ionized "column" of gas contained within the apertured dielectric is determined by the aperture geometry and may be readily controlled.

An object of the invention is to provide an improved low voltage radioactive voltage generating device.

Another object of the invention is to provide a low

2

voltage radioactive charging device having a controllable output voltage.

Another object of the invention is to provide an improved low voltage radioactive charger in which various specified voltages are readily attainable.

A further object of the invention is to provide an improved low voltage radioactive voltage generating device which is simple in structure and inexpensive to manufacture.

10 A further object is to provide an improved low voltage radioactive voltage charging device having an extensive field of applicability.

The invention will be described in detail with reference to the accompanying drawing in which:

15 Figure 1 is a schematic diagram of a low voltage radioactive voltage charging device, according to the invention;

Figure 2 is a graph illustrating the charging rates and limiting voltages of devices having different ion leakage paths which devices are fabricated in accordance with the invention; and

20 Figure 3 is a schematic diagram of a modification of the apparatus of Figure 1.

Similar reference characters are applied to similar elements throughout the drawing.

25 Referring to Figure 1, a source 11 capable of emitting high energy radioactive charged particles is mounted on a conductive support member 13. In the present example it will be assumed that the radioactive isotope employed is strontium⁹⁰, a beta particle emitter. It will be recog-

30 nized, however, that other beta particle emitters and other types of charged particle emitters also may be employed. Spaced from the support electrode 13 is a collector electrode 15 which may be formed from some suitable material such as aluminum. Intermediate the sup-

35 port electrode 13 and the collector electrode 15 a dielectric sheet or film 17 is disposed, the dielectric sheet comprising, for example, a sheet of polystyrene having an aperture 19 located in the travel path of a portion of the beta particles emitted by the source 11.

40 In operation: The high energy negatively charged beta particles emitted by the source 11 pass through the sup-

port electrode 13 and through the dielectric 17, each of which have low beta ray absorption, to the collector electrode 15 where they are absorbed almost completely to

45 charge the electrode 15 to some final voltage which is negative with respect to the potential of the source 11 and of support 13 therefor. The electric energy of this potential may be utilized to supply current and hence power to a desired utilization circuit 21. In the instant

50 example it will be seen that the source 11 and electrodes 13, 17, and 15 are illustrated as being in intimate contact with each other such that substantially no gas space exists between adjacent elements. Thus limited ionization occurs in the aperture space and there is only moderate dis-

55 charge of the potential developed between the source and the collector electrodes. Although some ions may be formed within the dielectric 17, by bombardment-induced-conductivity, this is not significant since the effective resistance of the dielectric material under bombardment is

60 quite large. This "contact" arrangement is not essential, however, since in some instances a spaced arrangement may be preferred. The spaced arrangement affords smaller values of capacity between electrodes 13 and 15 and hence higher charging rates.

65 As described previously, the Linder voltage charger normally charges to some ultimate and relatively high potential which is a function of a number of factors. This high voltage is reduced readily to a lower and more useful value, in accordance with the invention, by means of the aperture 19 located in the dielectric material 17 and situated in the travel path of a portion of the beta radi-

ation. A gas (air, for example) is contained within the confines of the dielectric material defining the aperture 19 and is ionized by the high energy radiation. If desirable the efficiency of such ionization may be enhanced by means of a magnetic field, indicated generally by the arrow H. This ionized column of gas intermediate the source 11 and the collector 15 acts as a resistor effectively shunting the voltage charger reducing the output voltage which it normally tends to develop. For the conditions illustrated in Figure 2, a .053" diameter hole causes the output voltage of the device to limit at 32 volts. If the dielectric material aperture 19 is made smaller, say .046", the resistance of the ionized column effectively shunting the charging is increased and the output potential thereof is approximately 110 volts. Other data are given for apertures having other diameters. It will be recognized, however, that other aperture configurations and geometries may be used to achieve desired resistances for obtaining output voltages as required.

Referring to Figure 3, a further embodiment of the invention is shown in which a single voltage generating or voltage charging device is adapted for supplying a wide range of output voltages. To this end the dielectric material 17 may be prepared to provide a threaded opening 23 adapted to receive a probe 25 longitudinally adjustable therein. The probe 25 preferably is formed from the same material as the dielectric sheet 17. With the probe 25 completely traversing and closing the aperture 19, it will be seen that the effective shunt resistance of the ionized gas column is high and the corresponding output voltage of the device is high. By progressively increasing the aperture size at the point wherein the probe traverses the aperture, the equivalent resistance of the gas column decreases and the output voltage of the device also decreases. By suitably shaping and sizing the probe 25 and by adjusting the relative position of the probe in the aperture substantially any desired output voltage readily may be obtained. Although the probe position is illustrated as being manually adjustable, it is pointed out that the probe position may be actuated in response to varying mechanical or electrical signal intelligence resulting in current being supplied to the load circuit 21 in an alternating fashion.

Thus the instant invention is directed to a new and improved radioactive voltage charging or voltage generating device having a controllable output voltage. The device is structurally simple and easy to fabricate. Also, a wide range of voltages are attainable which voltages are stable over extended periods of time and may be varied at will.

What is claimed is:

1. A voltage generating device comprising, a source of high energy charged particle emission, an electrode for collecting said charged particles to establish an electric potential relative to said source, and a controllable electrical charge leakage path disposed intermediate said source

and said electrode for controlling the level of said potential.

2. A voltage generating device comprising, a source of high energy charged particle emission, an electrode for collecting said charged particles to establish an electric potential relative to said source, and a controllable electrical charge leakage path comprising an ionizable gaseous region disposed intermediate said source and said electrode for controlling the level of said potential.

3. A voltage generating device as claimed in claim 2 including means for utilizing the electric energy of said potential.

4. A voltage generating device comprising, a primary source of high energy charged particle emission, an electrode for collecting said charged particles to establish an electric potential relative to said source, and an apertured dielectric member disposed intermediate said source and collector for providing a controlled electrical charge leakage path for controlling the level of said potential.

5. A voltage generating device comprising, a primary source of high energy charged particle emission, a collector electrode for collecting said charged particles to establish an electric potential relative to said source, and a dielectric member including an aperture disposed intermediate said source and said collector electrode, the confines of said dielectric member defining said aperture containing a gaseous medium capable of being ionized by a portion of said charged particle emission to provide a charge leakage path for controlling the level of said potential.

6. A voltage generating device comprising, a primary source of high energy radioactive charged particle emission, an electrode for supporting said charged particle source, a collector electrode spaced from said source for collecting said charged particles to establish an electric potential relative to the potential of said source, and an apertured dielectric member disposed intermediate and in contact with said support and collector electrodes for containing a gas capable of being ionized by said charged particle radiation for controlling the level of said potential.

7. A voltage generating device as claimed in claim 2 including means for controlling the geometry of said ionized gaseous region to control the level of said established potential.

8. A voltage generating device as claimed in claim 5 including a dielectric probe adjustably adapted to traverse said aperture to control the equivalent resistance of said gaseous medium.
